LAVATORY

Carl W. Sundberg, Bloomfield Hills, and Richard E. Hitchcock, Birmingham, Mich., assignors to Universal Rundle Corporation, New Castle, Pa., a corporation of Delaware

Filed June 19, 1964, Ser. No. 80,490

Term of patent 14 years

(Cl. D4—2)

Fig. 1

Fig. 2

Fig. 3

Fig. 5

Fig. 4

FIG. 1 is a perspective view of a lavatory embodying our new design;

FIG. 2 is a front elevational view thereof, partially in section;

FIG. 3 is a side elevational view thereof;

FIG. 4 is a top plan view of the same, and

FIG. 5 is a sectional view substantially along the line 5—5 of FIG. 4.

The dominant features of our design reside in the portions shown in full lines.

We claim:

The ornamental design for a lavatory, as shown and described.
